UNITED STATES PATENT OFFICE.

PHILLIPS P. BOURNE, OF SOMERVILLE, MASSACHUSETTS, ASSIGNOR TO THE BLAKE & KNOWLES STEAM PUMP WORKS, A CORPORATION OF NEW JERSEY.

AIR-PUMP.

No. 901,945.

Specification of Letters Patent.

Patented Oct. 27, 1908.

Application filed September 14, 1907. Serial No. 392,828.

To all whom it may concern:

Be it known that I, PHILLIPS P. BOURNE, a citizen of the United States, residing at Somerville, county of Middlesex, and State of 5 Massachusetts, have invented certain new and useful Improvements in Air-Pumps, fully described and represented in the following specification, and the accompanying drawings, forming a part of the same.

10 This invention relates to an improved air pump of the type now well known as double acting suction valveless pumps, the especial object of the invention being to provide a pump of this class in which the air and water 15 may be efficiently removed from a condenser and delivered, and which may have its suction inlet at the bottom of the pump, so that the condenser may be placed very low. This low placing of the condenser is especially 20 important in small boats, such as torpedo boats and yachts, but my improved air pump is of general application.

The especial feature of the invention consists in providing the pump with suction 25 valves below the plunger, so that the water, with some of the air and uncondensed vapors, is admitted to the cylinder below the plunger through the suction valves and delivered on the down-stroke, while the air and uncondensed vapor chiefly enter the pump cylinder 30 above the plunger through the valveless suction and is delivered on the up-stroke.

The preferred embodiment of the invention is illustrated in the accompanying drawings forming a part of this specification, in which the pump is shown in central vertical 35 section, and this construction will now be described and the features forming the invention then specifically pointed out in the 40 claims.

The pump illustrated is of the same type as that shown and described in United States Letters Patent to F. M. Wheeler, No. 674,819, dated May 21st, 1901, and need be described 45 here only to explain the present invention.

A is the vertical pump cylinder, B the plunger with plunger rod b, C the suction inlet, and D the delivery. The valveless suction passage c extends about the central portion 50 of the cylinder A, and is connected at one side by a passage 10 to the suction inlet C at the bottom of the pump. Below the cylinder A a suction valve plate d extends

across so as to form a suction chamber 11, from which the liquid passes through suction 55 valves 1 to the bottom of the cylinder A below the plunger B and to the pulsation chamber 12, from which the liquid is delivered through force valves 2 and vertical passage 13 to the main delivery D at the top of the 60 pump. Some of the air and uncondensed vapor entering at the suction inlet C passes through the foot valves 1, and is delivered to passage 13, but the most of the air and uncondensed vapor rises through passage 10, 65 enters the cylinder above the plunger B through valveless suction passage c, and is delivered at the top of the cylinder to the delivery C through force valves 3.

It will be understood that the invention is 70 not limited to the exact type of pump shown, nor to the specific arrangement of suction and delivery passages and valves illustrated, but that modifications may be made in the construction shown within the invention as 75 defined by the claims.

The invention is applicable to pumps having single cylinders, or with two or more cylinders, and the plungers may be driven by 80 any suitable means.

What I claim is:—

1. In a vertical double acting pump, a pump cylinder having a central valveless suction passage, a plunger, a suction chamber below the cylinder, a suction inlet connected to the suction passage and suction chamber, and suction valves controlling admission from the suction chamber to the cylinder below the plunger.

2. The combination with a vertical pump 90 cylinder A having central valveless suction passage c and plunger B, of suction inlet C at the bottom of the pump, passage 10 connecting the suction inlet and the valveless suction passage, plate d extending across the 95 bottom of the cylinder and forming suction and pulsation chambers 11, 12, and suction and force valves 1, 2 controlling admission and delivery below the plunger.

In testimony whereof, I have hereunto 100 set my hand, in the presence of two subscribing witnesses.

PHILLIPS P. BOURNE.
